Patented Dec. 10, 1963

197,090

PAIR OF EYEGLASSES

Pat M. Bredon, 3518 Crittenden, St. Louis, Mo.

Filed Oct. 11, 1961, Ser. No. 67,046

Term of patent 14 years

(Cl. D57—1)

FIG. 1

FIG. 2

FIG. 3

FIG. 4

FIG. 5

FIG. 6

FIG. 1 is a front elevational view of a pair of eyeglasses showing my new design;

FIG. 2 is a rear elevational view thereof;

FIG. 3 is a fragmentary elevational view thereof taken from the left side of FIG. 2;

FIG. 4 is a fragmentary cross-sectional view taken along the line 4—4 of FIG. 1;

FIG. 5 is a cross-sectional view taken along the line 5—5 of FIG. 1; and

FIG. 6 is a cross-sectional view along the line 6—6 of FIG. 1.

I claim:

The ornamental design for a pair of eyeglasses, as shown.
